UNITED STATES PATENT OFFICE.

WATKIN G. POWELL, WILLIAM B. POWELL, AND JAMES L. POWELL, OF SHADELAND, PENNSYLVANIA.

CLEVIS.

No. 839,196.

Specification of Letters Patent.

Patented Dec. 25, 1906.

Application filed February 3, 1906. Serial No. 299,344.

To all whom it may concern:

Be it known that we, WATKIN G. POWELL, WILLIAM B. POWELL, and JAMES L. POWELL, citizens of the United States, residing at 5 Shadeland, in the county of Crawford and State of Pennsylvania, have invented certain new and useful Improvements in Clevises, of which the following is a specification.

Our invention relates to an improvement in clevises, and it is especially constructed for use in connection with plows, whiffle-trees, &c., the object being to provide a clevis-pin which will remain in place. We 15 attain this object by the construction illustrated in the accompanying drawings, in which—

Figure 1 is a perspective view of the front part of a plow-beam and our improved clevis attached thereto. Fig. 2 is an enlarged side elevation of the pin. Fig. 3 is a side elevation of the clevis with the clevis-pin locked in position, part of the clevis being broken away to show detail of construction. Fig. 4 is a detail sectional view of the 25 head of the pin. Fig. 5 is a front view of the clevis-pin and clevis, and Fig. 6 is a perspective view of the clevis.

Similar letters refer to similar parts 30 throughout the several views.

The clevis A is constructed with the upper and lower holes a and a' , which register for the reception of the clevis-pin B. The upper opening or hole a is preferably larger 35 than the lower one for a purpose to be disclosed hereinafter. The lower opening or hole is formed with an offset a^2 to permit the passage through the hole of a shoulder b^2 on the end of the pin B. This shoulder is 40 formed by the reduction of the pin for a portion of its length, as shown at b' . This reduction is made upon the rear of the pin only, which causes the shoulder b^2 , and especially the upper part b^3 , to be eccentric with the reduced portion and the smaller opening or hole a' for a purpose which will later be obvious. The upper hole is made large enough 45 to receive the upper part of the pin and to permit the shoulder b^2 to pass through.

The pin is formed with a head b^4 , shaped so as to be easily lifted or turned with the thumb and forefinger. The head is provided with an eye b^5 , firmly secured in a hole b^6 , passing therethrough, and said eye receives

a U-shaped fastening device or latch C, whose 55 arms are bent downwardly at an angle, as at c , and inwardly toward one another, as indicated at $c' c'$. This fastening device is made of spring-wire, and it is held in an elevated position by forcing it above shoulders $b^7 b^7$, 60 formed on the opposite sides of the head of the pin. When the fastening device is forced down over these shoulders, its ends c and c' are confined between lugs $D D'$, 65 formed on the upper end of the clevis adjacent to the pin-hole. The purpose of these lugs is to limit the movement of the fastening device, and thereby prevent rotation of the pin by the jolting and jarring of the clevis due to the operation of the implement. 70

By the construction of the pin as described the application of draft or pull upon it will cause the pin to revolve, due to the eccentric, and assume its normal position in which it is locked by the fastening device. 75 The head of the pin is narrowed and extended, as shown, to give greater leverage for turning the pin when placing it in position or removing it.

We do not desire to be limited in the mechanical details of construction, and desire to indicate here that this clevis is not the only style to which our improvements may be applied. The invention may be applied to the twisted clevis, where the pin is normally in a 80 horizontal instead of a vertical position, and as a twisted clevis would involve no modification of our invention we have illustrated the one shape of clevis only. Our improved clevis can be readily applied wherever desired without any specially-designed hole with notches or grooves in the side, as is necessary with many clevises. An ordinary round hole of proper size can be made 85 through a whiffle-tree or wherever the clevis is to be coupled, and it will serve every purpose as well as if specially-formed holes were employed. 90

Having thus fully described our invention, what we claim as new, and desire to secure by Letters Patent, is—

1. The combination with a clevis of an eccentric-pin provided with a movable fastening device adapted to engage with the clevis and prevent rotation of the clevis-pin, 105 substantially as described.

2. The combination with a clevis, of an eccentric-pin provided with a movable fas-

tening device adapted to engage with the clevis and prevent rotation of the clevis-pin and means for holding the fastening device out of contact with the clevis, substantially as described.

3. The combination with a clevis provided with lugs on one arm thereof of an eccentric-pin provided with a movable fastening device adapted to engage with the said lugs to prevent rotation of the clevis-pin, substantially as described.

4. The combination with a clevis provided with registering pin-openings, the lower one of smaller diameter than the upper and having an offset notch or groove therein, of a headed clevis-pin formed with a reduced portion and a shoulder on the end thereof, the reduced portion being of substantially the same diameter as the lower opening, a spring fastening device pivotally attached to the head of the pin, shoulders on the opposite sides of said head adapted to hold the fastening device in an elevated position and means upon the upper side of said clevis adapted to engage the said fastening device when in a lowered position and prevent rotation of the clevis-pin from a normal position, substantially as described.

5. The combination with a clevis provided with stops on the upper arm thereof, of a clevis-pin provided with a shoulder on the end thereof formed to engage with the lower

arm of the clevis and prevent withdrawal and a latch adapted to be confined between said stops and thereby prevent rotation of the clevis-pin from its normal position with the shoulder in engagement with the lower arm of the clevis.

6. The combination with a clevis, of a clevis-pin formed with eccentric cylindrical portions and pin holes or openings in the clevis for the reception of the clevis-pin each of which is adapted to register with one of the eccentric portions thereof.

7. The combination with a clevis having clevis-pin holes of different diameters, of a clevis-pin formed with two eccentric portions each adapted to register with one of the pin-holes and means for locking the pin in position.

8. The combination with a clevis having clevis-pin holes of different diameters, of a clevis-pin formed with two eccentric portions each adapted to register with one of the holes, and a latch to secure the clevis-pin against rotation.

In testimony whereof we affix our signatures in presence of two witnesses.
